UNITED STATES PATENT OFFICE.

JOHN SPRING, OF NEW YORK, N. Y., ASSIGNOR TO THE W. & J. SLOANE,
OF NEW YORK.

DESIGN FOR A CARPET-BORDER.

SPECIFICATION forming part of Design No. 30,257, dated February 21, 1899.

Application filed January 16, 1899. Serial No. 702,370. Term of patent 3½ years.

To all whom it may concern:

Be it known that I, JOHN SPRING, a citizen of the United States, and a resident of the city, county, and State of New York, have invented a certain new and original Design for a Carpet-Border, of which the following is a specification.

My design as shown in the drawing consists in a new design for the border of a carpet.
10 The design is characterized by several rows or stripes of many closely-arranged geometrically-shaped figures varying in outline from each other, the principal figure in the most conspicuous stripe being diamond-like in outline. The said rows or stripes likewise vary considerably in width, and the numerous geo-

metrical shapes or figures of the design are suggestive of the figures of oriental rugs, thus imparting a rug-like character to the design as a whole.

20 What I claim as new, and desire to secure by Letters Patent, is—

The design for a carpet-border substantially as shown and described.

In testimony whereof I have signed my 25 name to this specification in the presence of two subscribing witnesses.

JNO. SPRING.
